UNITED STATES PATENT OFFICE.

HARRY A. CUMFER, OF CHICAGO, ILLINOIS, ASSIGNOR OF ONE-HALF TO ALBERT D. STEWART, OF HUTCHINSON, KANSAS.

PLASTER-RECEIVING BOARD.

Application filed August 17, 1922. Serial No. 582,344.

The invention relates to plaster-receiving board or composition lath.

One of the objects of the invention is to improve the construction of plaster receiving boards of the type made of two associated sheets, of which one is imperforate, by providing a structure that may conveniently be made by a machine from a constantly moving strip or sheet of suitable material.

10 Another object is to provide improved means for securing the sheets together and to the supporting wall.

15 A further object is to provide pockets for plaster between the two sheets by pressing parts of one or both sheets out of normal planes and cementing the displaced parts to the inner surface of the other sheet within the pockets or channels.

20 Another object is to provide a structure, of the class described, in which alternate channels are not so wide as the intermediate, plaster-containing channels.

25 Another object is to provide a plaster-receiving structure made of two united sheets, the outer sheet having perforate channels to receive plaster, the inner sheet having an enclosed imperforate channel, like walls of the channels being cemented together.

30 Other objects and advantages of the invention will hereinafter appear from a consideration of the following description, when taken in conjunction with the drawings, wherein:—

Fig. 1 is a sectional view of one form of 35 my invention.

Fig. 2 is a plan view of Fig. 1 showing parts in section.

Fig. 3 is a section on line 3—3 of Fig. 4 of another form my invention may take.

40 Fig. 4 is a plan view of Fig. 3.

Fig. 5 is a sectional view of another form which my invention may take.

Fig. 6 is a reduced plan view and section taken on line 6—6 of Fig. 5.

45 Fig. 7 is a section taken on line 7—7 of Fig. 8 showing another variation.

Fig. 8 is a reduced plan view of Fig. 7.

Fig. 9 is a similar view of a similar structure.

50 In all the views the same reference characters may be employed to indicate similar parts.

The structure is made of two sheets of suitable material having composite pockets

55 to receive plaster that may be applied to its outer surface, provided by displacement of portions of either sheet, the displaced portions of one sheet being cemented or otherwise secured to the other sheet.

60 In every instance the outer sheet is perforated to permit the plaster to enter the pockets or channels between the sheets and the inner or base sheet is imperforate to make the structure wind and water proof.

65 A suitable substance of which to make the structure is composition roofing made of a fibrous base 5 of felt, or the like, saturated with a water-resistant such as asphaltum or a compound thereof and coated on both sides with similar material 6, more or less 70 plastic when warm and which forms a strong cement when cold. The lower or base sheet 7 is imperforate. The upper or outer sheet 8 is formed into channels 9 and 10. The alternate channels 9 may be wider than the 75 intermediate channels 10.

The smaller channels are utilized to nail both sheets to the supporting wall 11.

70 In Figs. 5 and 6 parts of the base sheet are shown outwardly displaced to form continuous closed channels 12. In Figs. 1 and 2 cup-shaped spaced apart projections 12' are shown extending from the under sheet and cemented to the top sheet.

75 Contacting portions of the two sheets are 85 cemented together at 13 and the tops of the channels 12 and cups 12' are cemented to the inner surface of the wall 14 of the channel 9, at 15.

80 The channels 9 may be perforated at intervals in their side walls, as at 16, and in the intermediate walls 14, as at 17 and 17'.

85 In Figs. 3 and 4 the outer sheet 8 is slotted longitudinally at intervals to provide plaster receiving openings and the tongues 95 12^a are bent inwardly and cemented to the upper surface of the sheet 7. In Figs. 7 and 8 the slits are made so as to divide the tongues to provide base portions 20 which are parallel with the base sheet and cemented 100 thereto. This affords a larger surface contact than the form shown in Fig. 3. The parts 12—12' and 12^a form strengthening 105 projections extending from one sheet and cemented to the other sheet within the plaster-receiving channels 9. The side walls of Figs. 4 to 9, inclusive, may also contain openings 16 at suitable intervals.
